SLUG EJECTOR FOR COIN OPERATED MACHINES

Christof Weber, Los Angeles, Calif.

Application December 10, 1934, Serial No. 756,863

4 Claims. (Cl. 194—97)

This invention relates to an improved slug ejecting mechanism for coin operable devices, more particularly machines operable by coins of various values.

5 One object of the invention is to provide an improved means for preventing a magnetically arrested slug from obstructing the operation of the coin operable parts of the device.

Another object is to simplify the construction, 10 and at the same time render more positive and dependable the operation of certain coin actuated parts.

Still another object is to provide improved 15 means to expand certain wall members of the coin runway in order to discharge more effectively slugs and other undesired objects which may have been inserted into the machine.

Yet other objects, advantages and features of the invention may hereinafter appear.

20 Referring to the accompanying drawings, which illustrate a construction which is at present deemed to be a preferred embodiment of the invention,

Fig. 1 is a side elevation with parts in section, 25 the face plate nearest the observer being removed in order to disclose the dime passage and parts adjacent thereto, the sectioning being on line 1—1 of Fig. 2.

Fig. 2 is a vertical section on line 2—2 of 30 Fig. 1.

Fig. 3 is a vertical section on line 3—3 of Fig. 1, showing only the upper half of the device.

Fig. 4 is a horizontal section on line 4—4 of 35 Fig. 1.

Fig. 5 is a side elevation with parts in section, the face plate nearest the observer being removed in order to disclose the nickel passage and parts 40 adjacent thereto, the sectioning being on line 5—5 of Fig. 2.

Fig. 6 is a vertical section on line 6—6 of Fig. 2.

Referring in detail to the drawings, the casing 45 wherein the coin selecting elements are housed comprises the outer plates 5 and 6, and the inner plates 7 and 8. The plates 5 and 7 are in parallel spaced relation to each other in order to provide room for (among other things) a dime passage 9 between them, one edge and the top of said passage being bounded by the elongated raised spaced portion 10 and the opposite edge thereof being bounded by the spacer flange 11 and spacer plates 12 and 13. The plates 6 and 8 are also in a parallel spaced relation to each other, the purpose of this being to provide a nickel conducting 50 passage 14 between them.

55 Between the parallel, spaced inner plates 7

and 8 is a central space or chamber 15. In said space are mounted a double magnet 24 and certain other parts that affect the operation of the machine, which will be described later.

Returning to the dime passage 9, in the upper 5 part thereof is mounted a slug ejector lever 20 having at one end a finger 21 that normally restricts the width of the coin receiving slot 22, and at its opposite end a slug engaging head 23. Below said head 23 is mounted, within the central chamber 15, the double magnet 24 already referred to. Said head 23 is positioned to dislodge from said magnet any slug of ferrous metal which may have been arrested thereby. The lever 20 is pivotally supported at 25 and is restricted in its 10 swing by means of a slot 26 wherein travels a stud 27 carried by the lever, and is restored to normal position by a wire spring 28 attached to the opposite side of the plate 7. The spring 28 is arranged to act upon the inner portion of the stud 20 15 27, said stud having at its inner end a head 27b to keep the spring in engagement therewith.

A short distance below the magnet 24 the plate 7 has through it a ferrous slug discharge opening 31 opposite to which is located a deflector 25 plate 32 to direct through said opening any slug which may be dislodged from the magnet 24 by the action of the lever 20. Slugs so directed are discharged from the device through the space between the inner wall plates 7 and 8. 30

The lower edge of the upper and inclined portion of the dime passage 9 is formed by a weight detecting plate 33 which is pivotally supported at 34, said plate having its heaviest end portion at the side of its pivot which is nearest to the coin 35 admission slot 22; and its opposite end portion is tapered.

Spaced downwardly below the pivoted plate 33 is an abutment plate 35 which partially bridges the dime passage and the upper edge of which is 40 preferably straight, and is inclined reversely to the direction of the initial portion of said passage. The lower end of this straight edge terminates on an ear or lug 35a, and below said ear said plate is convexly curved in parallelism with an oppositely disposed concavity with which the spacer plate 13 is provided. Said plate 13 is notched at 13a opposite to the ear 35a. A double magnet 36 within chamber 15, acts upon ferrous 45 objects passing between the plates 13 and 35. 50

Wobble plates 11w are oscillably mounted adjacent the flange 11 on pins 11p (the holes through the plate being much larger than the pins) to slightly retard the speed of coins striking 55 against them.

As the dime passage continues downwardly it is furnished with a coin rebounding plate 39 which has a resilient arm 39a. Below this point the slug eliminating plate 41 as viewed in Fig. 1, 5 directs certain kinds of slugs across its slope 41d to the right, discharging them through the discharge passage 42, while the dimes are directed across its slope 41s to the left, to pass down the terminal portion of the dime passage. All 10 the parts thus far described within the dime passage 9 are duplicated within the nickel passage 14, excepting the plates 39 and 41, see Figs. 2 and 3. The slug discharge passage 42, however, occupies the entire width of the casing between its outer plates and scavenges from the 15 device slugs inserted as substitutes for either nickels or dimes.

In the lower part of the dime passage is mounted an escapement device which includes an up-standing weighted rack bar 45, an escapement lever 46 and an auxiliary lever 47. These two levers are pivotally mounted to cooperate with each other in such a manner that when a dime strikes the free end of the auxiliary lever said 20 lever acts upon the escapement lever and causes the weighted rack bar 45 to be released and to gravitate downwardly the distance between two adjacent teeth thereof. Thereupon the dime will descend farther and strike the lower end portion 25 of the pendant escapement lever, again operating the latter lever and thereby causing the bar 45 to descend another tooth. The dimes are directed against the levers 47 and 46 respectively by means of the extensions 10a and 10b with 30 which the spacing rise 10 is provided.

The auxiliary lever 47 is pivoted at 48 in position for its heel portion 49 to act upon an extension 50 with which the lever 46 is furnished near its pivot 51. Said lever 46 is restored to its 40 normal position by means of a wire spring 52.

The rack bar 45 carries a laterally extending arm 146 having an angularly directed portion 147 to serve as a finger hold for resetting the rack bar 45. With said arm cooperates a spring retracted slide 148 which is manually shiftable by 45 means of its handle 149 towards the right (Fig. 1) against the opposition of its spring. Said slide has an inclined cam edge portion 150 which is positioned to engage the arm 146 in such a way 50 as to afford a means to reset the rack bar by an extension of the slide. When a nickel only has been inserted the middle portion of said cam edge will engage the arm 146 at the beginning of the resetting operation. When a dime has been inserted 55 the rack bar together with its arm 146 will descend twice as far, and the entire length of said cam edge will be utilized in the resetting operation effected by a complete extension of the slide. It is to be understood that the device is 60 adapted to be used in conjunction with a vending machine wherein mechanism released by a partial descent of the rack bar will deliver articles valued at five cents, and mechanism will be released by a complete descent of the slide to deliver 65 articles valued at ten cents. Game plays or other privileges having dual values will likewise be thus controlled.

Whenever a genuine dime is inserted into the machine it will pass downwardly through the dime passage 10 without being diverted therefrom by any of the slug detecting means, and will finally drop into the coin receiving box 54, or other conventional coin receiver. This box is, however, shown provided with an operating rod 75 54a whereby it may be shifted to bring its bot-

tom opening 54b into register with an opening 54c in the slide 54d to discharge the dimes into a receiver 54e; or said slide may be moved to bring the openings 54b and 54c into alignment and thereby discharge the dimes into the receiver 54f. 5

In addition to the means which have been described for ejecting slugs of a circular character, there is provided, near the upper end of the casing, a contrivance for scavenging from the device toothpicks, pins and the like. For this 10 purpose oppositely disposed wings 55 and 56 are hingedly mounted close to the top of the casing normally forming parts of the outer walls thereof. Each of said wings is provided near its upper edge with a plurality of small apertures 57, the 15 apertures of one wing alining with those of the other, and also alining with apertures 58 through the casing. Through these alined apertures extend traction coil springs 59 having projecting end portions to receive rods 60 whereby the hinge 20 structure of the wings is completed. Pins 60a are secured through the flanges of the plates 7 and 8 adjacent to the coil springs 59 and pass loosely through fitted openings in the wings 55 and 56, to hold the wings in operative position 25 when opening and closing.

In order to swing said wings simultaneously outward against the opposition of their hinge springs 59, within the central chamber 15 is pivotally supported at 61 a common wing operating lever 62 the free end of which projects to the outside of the casing and terminates in a suitable hand hold or grip. Said lever has oppositely disposed studs 63 which project through slots 64 provided for them through the inner 30 walls of the casing. These studs act upon the inner cam faces of outwardly directed swells 65 in the wings and thus force the wings farther apart when the lever is depressed from the position shown in Fig. 1. When the wings are thus 40 swung outwardly, small articles lodged in the upper portions of the coin passages are permitted to fall from them or may be removed by the fingers or by a suitable tool.

The studs 63 of lever 62 are also positioned to 45 act upon the two slug ejecting levers 20 at the same time that said studs act upon the wings. Therefore the depression of lever 62 will clear the machine of any ferrous slugs in either of the coin passages, which may be sustained by the 50 magnet 24.

The lever 62 also has, within the central chamber 15, a downwardly extending arm 66 provided at its lower end with oppositely directed studs 67 which bridge the coin passages 9 and 14, slots 1s 55 and 8s being provided through plates 7 and 8 for these studs. The two coin detecting plates 33 have lower cam edges 33c upon which said studs 67 act to oscillate said plates to free them from obstructing objects, more particularly from 60 small moist articles like wet toothpicks. A spring 62x restores the lever 62 to normal position.

Nickels are admitted to the nickel passage 14 through the slot 22n, and a slot somewhat larger than the dime slot 22, and bounded above and below by parts which are substantially duplicates of those seen in the upper portion of Fig. 1.

Somewhat below the central portion of the nickel passage there is provided a pivotally mounted tiltable abutment 70 having a position- 70 ing spring 71 connected therewith below its pivot 72, and an upwardly directed acutely angular nose portion 73 thereabove. As viewed in Fig. 5, said abutment 70 is so located, and is so adjusted on its pivot as to direct the nickels towards the 75

right into the lower nickel passage 75, while slugs are directed towards the left into the slug exit passage 42. A spacer plate or rise 11 separates these passages.

5 Near the lower end of the passage 75 is suspended from a pivot 79 the pendant nickel operable lever 80 which has a stud 81 extending through a slot 82 to act upon the escapement lever 46 in the dime passage. Said lever 80 is normally held against a stop pin 83 by a spring 84. The plate or rise 10 has an inward extension 10b to direct the nickels against the lower portion of the pendant lever 46.

10 The edge of the nickel passage 14 farthest 15 from the nickel admission slot 22n is bounded by the spacing plate or rise 90. Near its lower end said spacing element 90 has an angular inward extension 91 to direct the nickels against the nickel operable lever 80.

15 Within the lower portion of the casing a spacer block 93 bridges the entire space between the outer plates 5 and 6 with the exception of the slug discharge passage 42 through which are discharged slugs used as substitutes for either 20 nickels or dimes. Said block 93 has a vertical passage 94 therethrough to receive with a working fit the escapement rack bar 45. Said block is also cut away on one side to provide a downward continuation of the dime passage 9, and on 25 the opposite side to make room for the lower nickel passage 75.

30 Above the spacer block 93 a filler block 95 aids in supporting the magnet 24 and occupies parts of the center chamber 15 not required to furnish 35 room for other purposes.

35 The parts 54 to 54f already described for disposing of the dimes discharged from the lower end of the casing are of sufficient width to receive also the nickels delivered from the lower nickel 40 passage 75, and these parts may be operated to dispose of the nickels in the same manner as the dimes.

45 The action of the device upon coins and coin substitutes will now be more fully described.

50 Genuine dimes will not be too wide or too thick to enter the admission opening 22 and will upon entering said opening, drop upon the inclined weight detecting lever 34 and will be sufficiently supported thereby to be directed against the inner edge of the bevel face 10d to rebound sufficiently to clear the scavenging opening 31. But slugs heavier than dimes will tilt the lever 33 as indicated in dotted lines and by it will be directed through the scavenging opening 31. A 55 light slug will not rebound enough from the part 23 to escape the opening 31, but will fall short of the peak 35x of the plate 35. A slug of the same weight and size as a dime, but of a more ferrous character would take the same course as a dime 60 till it reached the magnet 24 which would arrest it until the insertion of another dime would operate the scavenging lever 20 and direct such a slug into the scavenging opening 31.

65 A dime rebounding from the hammer portion 23 of the striker 20 will roll down the inclined top edge of abutment 35 and will pass over its ear 35a whereupon it will strike the wobble plate 11w and then move across the notch 13a and into the arcuate passage between the plates 13 and 35. Said wobble plate and notch cooperate to decrease the speed of the dime in order to prevent it from passing over the insulated double magnet 36 at too great a speed. The magnet 36 will also exert a retarding influence upon the dime.

70 75 A genuine dime, thus retarded, will be directed

across the slope 41s of the segregating member 41, but a slug of a kind not thus subjected to retardation will strike against the resilient finger 39a of the plate 39 and will be thereby thrown back over the slope 41d of the member 41, 5 whence the slug will be scavenged from the device through the passage 42.

10 The action of dimes upon the escapement levers 45 and 46 will be readily understood from the preceding description of the mechanical construction.

15 Down to, and including the lower magnet 36 the device acts upon the nickels in the same way and by means of the same parts except that the sizes, adjustment and positions of the parts are somewhat varied where this is necessary. Below the magnet 36 the nickel passage (see Fig. 5) is provided with the tilttable abutment 70 which detects whether or not the object striking it exerts the same amount of impact as that of a nickel, 20 and also whether or not such an object is moving along the inclined path which a nickel will follow. The action of the nickels upon the escapement device through the lever 80 has already been sufficiently described. 25

I claim:

1. In a coin selecting mechanism a housing, a pair of spaced parallel coin chutes mounted in said housing and extending in a tortuous path from near the top to near the bottom thereof, 30 the upper portion of the outer walls of said chutes being hinged at their upper edges to form wings arranged to have their lower edges swing outwardly, coil springs connecting said wings and acting to normally maintain the same in 35 their closed positions, openings in adjacent sides of said chutes below said wings in register, a magnet mounted between said chutes in register with said openings, an ejector lever rockably mounted in each of said chutes at the upper ends 40 thereof and having one end partially obstructing the chute inlet openings and its other end formed in a downwardly depending head normally resting immediately above the magnet openings, 45 slug openings in adjacent sides of the chutes immediately below the magnets, deflectors mounted on the walls of the chute for deflecting slugs out of the coin chutes through the slug openings, a slug chute between the coin chutes in communication with the slug openings, a vibrating lever 50 pivotally mounted intermediate its ends in each of said coin chutes at the inlet thereof and forming a portion of the lower wall of the coin chute, a substantially T-shaped auxiliary lever rockably mounted, at one end of its horizontal leg, between said coin chutes immediately above the ejector levers and having the other end of the horizontal leg terminating without the housing and the free end of its vertical leg arranged to operatively engage the vibrating levers and rock 55 the same, studs projecting from the said auxiliary lever arranged to engage the ejector levers and said wings and operate the same when the outer end of the auxiliary lever is depressed, a repelling magnet mounted between the coin 60 chutes below the slug openings in communication with the coin chutes, a wobble plate in each coin chute above the last magnet for retarding the passage of coins thereby, a rebound plate mounted in one of said chutes below the repelling 65 magnet, a slug eliminator mounted below the rebound plate arranged to direct coins and slugs in opposite directions.

2. In a coin selecting mechanism a housing, a pair of spaced parallel coin chutes in said hous- 75

ing extending from near the top to near the bottom thereof, openings in adjacent sides of said chutes in register, a magnet mounted between said chutes in register with said openings, an 5 ejector lever rockably mounted in each of said chutes at the upper ends thereof having one end partially obstructing the inlet openings of the chutes and its other end terminating in a head normally resting immediately above said magnet 10 openings, slug openings in the adjacent sides of the chutes immediately below the magnet openings, deflectors on the sides of the coin chutes for deflecting slugs through said slug openings, a slug chute between the coin chutes in communication 15 with the slug openings, a weight detector lever pivotally mounted intermediate its ends in each of said coin chutes at the inlet thereof and forming the lower wall thereof, a substantially T-shaped auxiliary lever rockably mounted at one 20 end of its horizontal leg between the coin chutes immediately above the ejector levers and having its other end of the horizontal leg terminating without the housing and the free end of the vertical leg positioned to rock the weight 25 detector levers when said auxiliary lever is depressed, a repelling magnet mounted between the coin chutes below the slug openings in communication with the coin chutes, a wabble plate in each of the coin chutes above said last magnet, 30 a rebound member mounted in one of the chutes below the repelling magnet, and a slug eliminator mounted beneath the lower end of each chute for directing slugs out of the device.

3. In a coin selecting mechanism, a pair of 35 spaced parallel coin chutes extending substantially vertically, the inlets to the chutes being at the top and the outlets at the bottom, openings in adjacent sides of said chutes near the upper ends thereof in register, a magnet positioned between 40 said chutes in register with said openings, ejector levers mounted at the upper ends of the chutes having one end normally restricting the inlets thereof and having their other ends terminating in downwardly depending heads nor- 45 mally resting above said magnet openings, slug openings in adjacent sides of said chutes below the magnet openings, deflectors on the sides of the chutes for deflecting slugs detached from said magnets by the head of the ejector levers out of 50 the coin chutes and through the slug openings, a slug chute between the coin chutes in communication with the slug openings, a balanced weight detector lever pivotally mounted intermediate its ends in each of the coin chutes at the inlet there- 55 of and forming a portion of the lower wall of said chute, a substantially T-shaped auxiliary lever

rockably mounted at one end of its horizontal leg between the coin chutes above the ejector levers and having the other end of said horizontal leg terminating in a hand member, and the free end of its vertical leg positioned to rock the weight 5 detector levers when the hand member is depressed, a repulsion magnet positioned between said coin chutes below the slug openings in communication with the coin chutes, a wabble plate in each of the coin chutes above said last magnet, 10 a resilient rebound member mounted in one of said coin chutes below the repulsion magnet, and a slug eliminator at the lower end of said last mentioned chute for directing slugs from said rebound member out of the machine. 15

4. In a coin selecting mechanism a housing, a pair of spaced parallel coin chutes in said housing extending from near the top to near the bottom thereof, openings in adjacent sides of said chutes in register, a magnet mounted between said chutes 20 in register with said openings, ejector levers rockably mounted in said chutes at the upper ends thereof having one end restricting the inlet of the chutes and the other end terminating in a head normally resting immediately above the 25 magnet openings, slug openings in the sides of said coin chutes below the magnet openings, deflectors on the sides of the coin chutes for deflecting slugs from said magnet out of the coin 30 chutes through the slug openings, a slug chute between the coin chutes in communication with the slug openings, a weight detector lever pivotally mounted intermediate its ends in each of said coin chutes at the inlets thereof and forming a portion 35 of the lower wall thereof, a substantially T-shaped auxiliary lever pivotally mounted at one end of its horizontal leg between the coin chutes immediately above the ejector levers and having the other end of said leg terminating without the housing and forming a hand member, and the free 40 end of the vertical leg positioned to rock the weight detector levers when the hand member is depressed, a wabble plate in each of the coin chutes arranged to retard the speed of coins passing therethrough, openings in the sides of the 45 chutes below said wabble plates, a repulsion magnet between the coin chutes in register with said last openings arranged to increase the speed of diamagnetic slugs passing through the coin through the coin chutes, a rebound member 50 mounted below said repulsion magnet in one of said chutes and positioned to receive impact of diamagnetic slugs, and a slug eliminator beneath the lower end of each chute for directing slugs and coins in opposite directions. 55

CHRISTOF WEBER.
